(57) **CLAIM**

The ornamental design for a bipolar cutting electrode, as shown and described.

DESCRIPTION

FIG. 1 is a front, right side, bottom perspective view of a first embodiment of a bipolar cutting electrode showing our new design;

FIG. 2 is a front, left side, top perspective view thereof;

FIG. 3 is a front elevation view thereof;

FIG. 4 is a right side elevation view thereof; the left side elevation view being a mirror image thereof;

FIG. 5 is a rear elevation view thereof;

FIG. 6 is a top elevation view thereof;

FIG. 7 is a bottom elevation view thereof;

FIG. 8 is a front, right side, bottom perspective view of a second embodiment of a bipolar cutting electrode showing our new design;

FIG. 9 is a front, left side, top perspective view thereof;

FIG. 10 is a front elevation view thereof;

FIG. 11 is a right side elevation view thereof; the left side elevation view being a mirror image thereof;

FIG. 12 is a rear elevation view thereof;

FIG. 13 is a top elevation view thereof;

FIG. 14 is a bottom elevation view thereof;

FIG. 15 is a front, right side, bottom perspective view of a third embodiment of a bipolar cutting electrode showing our new design;

FIG. 16 is a front, left side, top perspective view thereof;

FIG. 17 is a front elevation view thereof;

FIG. 18 is a right side elevation view thereof; the left side elevation view being a mirror image thereof;

FIG. 19 is a rear elevation view thereof;

FIG. 20 is a top elevation view thereof; and,

FIG. 21 is a bottom elevation view thereof.

The broken lines in the drawings are for the purpose of illustrating unclaimed portions of the bipolar cutting electrode and form no part of the claimed design.
